United States Patent

Des. 241,388
Patented Sept. 14, 1976

241,388

STAND FOR POTTED PLANTS

Roger U. McClung and Mary S. McClung, both of
R.R. 1, Liberty, Mo. 64068

Filed Dec. 15, 1975, Ser. No. 641,694

Term of patent 14 years

Int. Cl. D6—04

U.S. Cl. D6—28

Fig. 1.

Fig. 2.

Fig. 3.

Fig. 4.

Fig. 5.

FIG. 1 is a perspective view of a stand for potted plants embodying our new design.

FIG. 2 is an enlarged side elevational view thereof, the other sides being identical.

FIG. 3 is an enlarged top plan view thereof.

FIG. 4 is an enlarged bottom plan view thereof.

FIG. 5 is an enlarged sectional view looking downwardly toward a base portion thereof and taken on line 5—5 of FIG. 2.

We claim:

The ornamental design for a stand for potted plants, as shown and described.
